ATTORNEY

UNITED STATES PATENT OFFICE.

CHRISTOPHER J. LAKE, OF BRIDGEPORT, CONNECTICUT.

AIRPLANE.

1,307,134.

Specification of Letters Patent. Patented June 17, 1919.

Application filed August 28, 1917. Serial No. 188,683.

To all whom it may concern:

Be it known that I, CHRISTOPHER J. LAKE, a citizen of the United States, and resident of Bridgeport, in the county of Fairfield 5 and State of Connecticut, have invented certain new and useful Improvements in Airplanes, of which the following is a specification.

This invention relates to airplanes and 10 my improvement is directed particularly to a novel form of aerofoil, so devised and arranged with respect to the means by which it is mounted that it is susceptible of employment both as an elevator and as a directional rudder. This new form of aerofoil 15 may thus be termed a composite control member.

The dual functions possessed by this control member are imparted therein through 20 a system of biaxial mounting resembling a Cardan-joint, whereby said member may swing about a longitudinal axis, also about a transverse axis, and besides have composite centers of movement created by joint pivotal action of both axes.

By means of the universal character of movement available for this control member it can be caused to operate either solely 25 as an elevator, solely as a directional rudder, or as partaking of the functions of both elevator and rudder.

Other features and advantages of my said invention will hereinafter appear:

In the drawing: 30 Figure 1 is a side elevation of a tractor biplane having my improved aerofoil.

Fig. 2 is a plan view of said device.

Fig. 3 is an enlarged detail view, in front elevation, showing the means of mounting 40 the aerofoil as an empennage device.

Fig. 4 is a side elevation of Fig. 3, and

Fig. 5 is a plan view taken through the line 5—5 of Fig. 3.

By way of example only my improvement 45 is here shown as applied to a tractor bi-plane having the fuselage 1, main supporting aerofoils 2, and control aerofoil 3.

In presenting a practical form of bi-axial mounting for aerofoil 3 I wish to make clear 50 that such form is purely arbitrary and non-limiting, the essential characteristic of the pivotal arrangement employed being that the separate axes, whether intersecting or in different planes, must be in perpendicular relation to each other.

Thus the control aerofoil 3 is here shown

as mounted at the rear end of the fuselage, being carried upon a longitudinal pivot 4, that is journaled in a yoke 5; which latter is mounted in bearings 6, by transverse pivots 60 7. Therefore the aerofoil 3 is capable of swinging both laterally and longitudinally, and also of swinging through arcs representing the combined motions of its pivotal supports. 65

The yoke or mount 5, as here shown, is represented as a closed link or ring, with spaced side members 8, which are inclined from the center downwardly and divergently 70 in the shape of a wide V, its end members 9 having the bearings 6, and its upper central portion 10 affording the bearings for the pivot 4.

A sleeve 11 is mounted upon the pivot 4 and itself carries upwardly diverging arms 75 12, which serve as supports for the aerofoil 3, which is engaged thereby in the region of the center of pressure.

The mount 5 is in fact a pivotal support for the aerofoil and is itself pivotally carried by 80 the fuselage, the respective pivotal axes bearing right angular relation to each other.

A sector 13 is connected at its ends to the arms 12, depending therefrom, and being fitted with control cables 14, 15, which, respectively, hug opposite sides of said sector, as in a peripheral groove therein, and cross each other below the pivot 4. As a matter of convenience, with the form of mount here shown, the pivots 7 may be hollow, to allow 90 the passage of the cables therethrough; said cables passing thence over pulleys 16, which may be journaled in lugs 17 that are borne by the fuselage.

Lever arms 18 extend from the yoke 5, and 95 control cables 19 are connected to the ends of said arms.

It will be apparent that by manipulation of the cables 14 and 19, either separately or conjointly, the aerofoil 3 may be caused to 100 assume any desired angle for control of the airplane.

The aerofoil 3 is here shown as set with its chord at a rearwardly converging angle 105 relatively to its longitudinal axis or pivot 4, whereby said aerofoil may normally present a considerable attacking angle of incidence; this angle of course being variable through the control and the mounting means described, whereby said aerofoil is caused to 110 operate with all the desirable functions of an elevator, and whereby these functions be-

come merged into those other functions of the same aerofoil when it is swung about its longitudinal axis to give horizontal direction to the airplane. Hence, it will be easily 5 perceived that the directional facilities of this aerofoil are composite, in so much that, while exercising support, it may, in the different arcs of its movement, be employed to guide the airplane vertically, laterally, and 10 through all intermediate directional ranges.

I find that the angular arrangement here indicated between the aerofoil 3 and its longitudinal pivot 4, enables the control action to be quickly responsive, because, thereby, 15 when swinging the aerofoil from its central position only about said pivot, its angle of incidence becomes progressively increased with relation to the longitudinal axis of the airplane.

20 Variations may be resorted to within the spirit and scope of my said invention and parts thereof used without others.

I claim:—

1. In an airplane, in combination, an auxiliary aerofoil, and a bi-axial mount therefor, said aerofoil having longitudinal pivotal movement and presenting, for vertical control, an angle of incidence in the line of flight, and said aerofoil being turnable 30 about a lengthwise axis, in the central vertical plane of, and so inclined forwardly downward to the longitudinal axis of the airplane, that said aerofoil, for directional control, presents varying angles of incidence to said 35 longitudinal axis.

2. In an airplane, in combination, an auxiliary aerofoil, and a bi-axial mount engaging said aerofoil in the region of the center of pressure thereof, said aerofoil having longitudinal pivotal movement and presenting, for vertical control an angle of incidence in the line of flight, and said aerofoil being turnable about a lengthwise axis, in the central vertical plane of, and so inclined for- 40

wardly and downward to the longitudinal 45 axis of the airplane, that said aerofoil, for directional control, presents varying angles of incidence to said longitudinal axis.

3. In an airplane having a fuselage, a main supporting unit, and a control aerofoil, 50 the combination of a bi-axial mount whose respective axes are perpendicular to each other, a transverse pivot connecting said mount and fuselage, and a longitudinal pivot connecting said mount and aerofoil, the 55 chord of said aerofoil converging rearwardly with relation to the axis of its pivot, whereby, in its lateral movement, said aerofoil varies its angle of incidence relatively to the longitudinal axis of said airplane. 60

4. In an airplane having a fuselage, a main supporting unit, and a control aerofoil, the combination of a bi-axial mount whose respective axes are perpendicular to each other, said mount comprising a longitudinally arranged pivot, means revoluble on 65 said pivot and engaging said aerofoil in the region of the center of pressure thereof, a bearing for said pivot, and a transverse pivot to revolvably engage said bearing. 70

5. The combination, with a control aerofoil for airplanes, of a bi-axial mount, said mount comprising a longitudinally arranged pivot, a bearing member, and a transverse pivot for said bearing member, and means 75 for revolvably connecting said aerofoil with said longitudinally arranged pivot, whereby said aerofoil may swing between a central longitudinal position and respective vertical positions at opposite sides of said mount. 80

Signed at the borough of Manhattan, in the city, county and State of New York, this 27th day of August, A. D. 1917.

CHRISTOPHER J. LAKE.
